SWIM SUIT OR THE LIKE

Arthur H. Rinehart, Glen Rock, N.J. (½ Hawthorne
Knitting Mills, 31 Forest Ave., Hawthorne, N.J.)

Filed May 10, 1962, Ser. No. 70,067

Term of patent 14 years

(Cl. D3—17)

FIG. 1 is a front perspective view of a swim suit showing my new design,

FIG. 2 is an enlarged front elevational view of one of the breast cups of the swim suit, of my design, showing the essential feature of the invention,

FIG. 3 is a side elevational view of the cup shown in FIG. 2,

FIG. 4 is a top plan view thereof, and

FIG. 5 is a bottom plan view thereof.

The back of the swim suit is of a conventional cut.

I claim:

The ornamental design for a swim suit or the like, as shown and described.
